UNITED STATES PATENT OFFICE.

HUBER H. ROOT, OF MEDINA, OHIO, ASSIGNOR TO THE A. I. ROOT COMPANY, OF MEDINA, OHIO, A CORPORATION OF OHIO.

SPECIMEN BOX.

Application filed May 19, 1925. Serial No. 31,421.

My invention concerns boxes or containers for articles which make it of great importance that though necessarily made of pieces of wood, the joints unavoidable in the construction shall be so tight as to be proof against the admission of insects or air, and in particular to boxes for mounting entomological or other natural history specimens. In such a box it is important that no joint exists in the box sufficiently open to permit the entrance of moths or other insects, because they feed upon and destroy such specimens. Although the making of such boxes is done with great skill and of kiln-dried lumber, the best of them being put in dry places or subject to atmospheric and temperature changes will from the shrinkage and expansion of the wood that occurs have cracks where the cover meets the body of the box. These cracks are of sufficient size to permit the entrance of moths or other insects. The object of my invention is to provide a box or container which being of necessity openable for access to its interior may at all times, when in a closed condition, be sealed against the passage of objectionable things into the box. My invention consists in whatever is described by or is included in the terms or scope of the appended claims.

In the annexed drawings:

Fig. 1 is a perspective view of a box embodying my invention;

Fig. 2 is a cross section thereof;

Fig. 3 is a perspective view of the mounting board part of the box.

Describing in detail the box or container shown in the drawings, it is of rectangular form consisting of four side walls, 10, consisting of strips of wood securely united at the four corners and with a top cover or closure, 11, of glass which at its edges fits in grooves in the inner sides of the side walls, the joints being hermetically sealed, as by the use of white shellac or sodium silicate or secured by paper to the top edges. The glass, of course, is to enable one to see specimens that are to be examined while mounted in the box. The box sides rest at their bottom edges upon a rectangular bottom closure 50 whose dimensions may match the lateral dimensions of the box sides, which closure and the box sides are separable so as to give access to the interior of the box, and also to enable the bottom closure to be used by itself 55 as a mounting board for specimens. It is a

common practice to mount specimens upon a mounting board and then later to transfer them to a box, but by my invention a separate mounting board is unnecessary. My combined closure and mounting board in one 60 form consists of a thin rectangular board, 12, to the upper side of which is secured a sheet of easily pinned or penetrated material preferably a fibrous material such as cork or peat, such sheet, 13, being of lateral dimensions matching the internal lateral dimensions of the box sides so that when the box sides are in position they are telescoped over the sheet and are thereby centered.

At each of the four edges of the sheet, 13, 70 are outwardly movable flaps, 14, which normally tend to bodily move outward, which when the side walls are telescoped over the sheet are engaged by the inner sides of the side walls and yieldingly press outward 75 against the same with sufficient force to make the desired tight joint. Normally, of course, these flaps when not engaged by the side walls extend outward beyond what would be the plane of such side walls when 80 the latter are in position. The flaps, 14, may be the marginal portions of a rectangular sheet of heavy paper, 15, which is secured by pins, 16, or otherwise, to the penetrable sheet, 13, the sheet, 15, being slit or 85 cut away at each of its four corners to allow the flaps to be turned downwardly. It is desirable that the surface of the mounting board shall be white or some other light color to furnish a suitable background for 90 specimens, and the sheet of paper admirably combines the desired properties for a background and the packing strip on the margins, and of course, it may be readily penetrated by the pins to which the specimens 95 are attached. Of course, my invention is not restricted to the use of a continuous sheet, and if desired the packing strip or flap at each of the four sides may be a separate piece suitably secured in place.

If desired attaching means may be provided to secure together the separable closure and the box proper, and by box proper I mean the member which includes the side walls and the permanent closure, such as the 105 plate of glass at the top of the space between the side walls, but the friction of the packing strips against the side walls may serve to prevent accidental displacement in handling the box by holding it at the bottom.

Such fastening means may be hooks, 16, pivoted to the front side wall and pins, 17, projecting from the edge of the closure, 12, with which the hooks may be moved into and out 5 of engagement, and eyes 18, attached to the back edge of the closure, 12, and pins, 19, projecting from the back wall which engage said eyes, 18.

What I claim is:

1. A box or container comprising side walls, closures for the space between the side walls applied to the opposite edges thereof with sealed joints, at least one of such closures being separable from the side walls, and the sealing means between the same and the side walls consisting of laterally and bodily movable packing strips situated between the inner sides of the side walls and marginal surface of the closure. 10

2. A box or container comprising side walls, closures for the space between the side walls applied to the opposite edges thereof with sealed joints, at least one of such closures being separable from the side walls, and the sealing means between the same and the side walls consisting of laterally and bodily movable packing strips situated between the inner sides of the side walls and marginal surface of the closure, and fastening means to hold together the side walls and the separable closure. 20

3. A box or container comprising side walls, closures for the space between the side walls, one of which is permanently secured with a sealed joint to the side walls, and the other is separably secured to the side walls, a laterally and bodily movable joint-sealing means between the separable closure and the side walls, the permanent closure being transparent and the other closure having a specimen attaching surface within the box and having marginal edges between which and said walls said joint-sealing means is situated. 30

4. A box or container comprising side walls, closures for the space between the side walls, one of which is permanently secured with a sealed joint to the side walls, and the other is separably secured to the side walls, the permanent closure being transparent and the other closure having a specimen attaching surface within the box that consists of a sheet of readily penetrable material that extends within and is overlapped at its edges by the side walls and laterally and bodily movable packing strips between said sheet and said side walls, said packing strips being integral with the readily penetrable sheet that extends over said first mentioned sheet, both sheets being plane and rectangular, and the sheet having the packing strips being slit at the corners. 40

5. A box or container comprising side walls, closures for the space between the side walls, one of which is permanently secured

and said side walls, said packing strips being integral with a readily penetrable sheet that extends over said first mentioned sheet. 50

6. A box or container comprising side walls, closures for the space between the side walls applied to the opposite edges thereof with sealed joints, at least one of such closures being separable from the side walls, and the sealing means between the same and the side walls consisting of laterally and bodily movable packing strips situated between the inner sides of the side walls and marginal surface of the closure, and fastening means to hold together the side walls and the separable closure. 60

7. A box or container comprising side walls, closures for the space between the side walls applied to the opposite edges thereof with sealed joints, at least one of such closures being separable from the side walls, and the sealing means between the same and the side walls consisting of laterally and bodily movable packing strips situated between the inner sides of the side walls and marginal surface of the closure, and fastening means to hold together the side walls and the separable closure at the front and back of the box, respectively. 70

8. A box or container comprising side walls, closures for the space between the side walls, one of which is permanently secured with a sealed joint to the side walls, and the other is separably secured to the side walls, the permanent closure being transparent and the other closure having a specimen attaching surface within the box that consists of a sheet of readily penetrable material that extends within and is overlapped at its edges by the side walls and laterally and bodily movable packing strips between said sheet and said side walls, said packing strips being integral with the readily penetrable sheet that extends over said first mentioned sheet, both sheets being plane and rectangular, and the sheet having the packing strips being slit at the corners. 80

In testimony whereof I hereunto affix my signature. 90

with a sealed joint to the side walls, and the other is separably secured to the side walls, the permanent closure being transparent and the other closure having a specimen attaching surface within the box that consists of a sheet of readily penetrable material that extends within and is overlapped at its edges by the side walls and laterally and bodily movable packing strips between said sheet and said side walls, said packing strips being integral with a readily penetrable sheet that extends over said first mentioned sheet.

6. A box or container comprising side walls, closures for the space between the side walls applied to the opposite edges thereof with sealed joints, at least one of such closures being separable from the side walls, and the sealing means between the same and the side walls consisting of laterally and bodily movable packing strips situated between the inner sides of the side walls and marginal surface of the closure, and fastening means to hold together the side walls and the separable closure. 75 80

7. A box or container comprising side walls, closures for the space between the side walls applied to the opposite edges thereof with sealed joints, at least one of such closures being separable from the side walls, and the sealing means between the same and the side walls consisting of laterally and bodily movable packing strips situated between the inner sides of the side walls and marginal surface of the closure, and fastening means to hold together the side walls and the separable closure at the front and back of the box, respectively. 95

8. A box or container comprising side walls, closures for the space within the side walls, one of which is permanently secured with a sealed joint to the side walls, and the other is separably secured to the side walls, the permanent closure being transparent and the other closure having a specimen attaching surface within the box that consists of a sheet of readily penetrable material that extends within and is overlapped at its edges by the side walls and laterally and bodily movable packing strips between said sheet and said side walls, said packing strips being integral with the readily penetrable sheet that extends over said first mentioned sheet, both sheets being plane and rectangular, and the sheet having the packing strips being slit at the corners.

In testimony whereof I hereunto affix my signature. 115
